UNITED STATES PATENT OFFICE

2,214,735

ELECTRICAL COMPENSATOR

Laurence Batchelder, Cambridge, Mass., assignor to Submarine Signal Company, Boston, Mass., a corporation of Maine

Original application January 6, 1933, Serial No. 650,535. Divided and this application November 21, 1936, Serial No. 112,058

4 Claims. (Cl. 177—386)

This application is a division of my copending application Serial No. 650,535, filed January 6, 1933, issued August 3, 1937, Patent No. 2,088,580, and relates to electric compensators.

5 Electric compensators have been known for a considerable time and have been used among other purposes for the directive reception of underwater noises and signals. Considerable development along these lines was first made during the World War when the use of the so-called 10 multispot compensation was first evolved. Electric compensators were used with a group of receivers submerged in the water, either mounted within the vessel or carried over the side, for 15 detecting the presence of other vessels such as enemy submarines or warships. Compensators used in this manner have also found application along commercial lines and have been used successfully in preventing collisions between vessels 20 as well as determining the direction of some known source of sound.

In a compensator of the present type which may be called a group compensator, the groups are first individually compensated and then compensated as a whole between the two indicating or telephone devices in the same general way as in the prior art. In the compensators of the prior art having a so-called binaural line, that is the line which compensates each group for a final 25 balance, a switching arrangement is used which opens the line successively at different sections. The electrical contacts at the points where these openings occur are often poor, because of dust or small particles which come between the 30 contacting surfaces with the result that some resistance is set up in the circuit. This increases the resistance on the coil side of the line and produces a distortion effect which reacts very unfavorably in creating false observations and 35 inaccurate balances when making a compensator setting. Besides this, the added resistance increases the attenuation of the line.

In my copending application Serial No. 600,191, filed March 21, 1932 issued February 16, 1937, 40 as Patent No. 2,070,570, I showed how these difficulties could be overcome by employing a switch arrangement in which the line is varied at the common side and the line is therefore preserved intact while the switch is being moved from section to section.

This switching arrangement had the further advantage that it was possible to increase or decrease the length of the line a half section at a time so that the sections could be made twice the size that otherwise could be used. The sec-

tions could therefore be made twice the size necessary to produce the maximum change of retardation in the motion of the compensator switch allowable to preserve the continuity of the impression to the observer. The result was that a compensator of fewer sections could be built and that both the intermediary and final lines could be made to have the same time lag.

5 In my Patent No. 2,088,580, referred to above, I disclosed a further improvement in the compensator switch whereby the number of inductive section elements could be reduced by utilizing a pair of bridging coils which the compensator switch connects in parallel with the normal coils of the retardation line. By this means it is possible to obtain a mid-series termination of the line as well as the usual mid-shunt termination when only a single two-terminal inductance is used in each section. This applied particularly to the binaural lines and made it possible to 10 reduce the number of coils in these lines to half the number previously used.

15 The present invention provides a further improvement in the compensator switch and relates particularly to the maximum lines. In this case 20 the number of coils and condensers is not reduced, but a perfect termination of each section as the length of the line is varied is made possible whereby the accuracy of the compensator is increased. In the prior art the use of 25 a pair of bridging coils which can be connected in parallel with one of the coils of the retardation line has already been suggested but such arrangements have not been for the same purpose as in the present invention, namely to provide a proper termination of a portion of the line when its length is being varied. According 30 to the present invention the bridging coils are given the same inductance values as those of 35 the coils in the line proper.

40 This and other features of the present invention will be evident from the following description taken in connection with the accompanying drawings in which Figure 1 shows a schematic wiring diagram of the compensator including the 45 retardation lines both binaural and maximum and the compensator switch; Figure 2 shows a development of a part of the switch controlling the maximum line; and Figure 3 shows schematically a modification of Figure 1 which nevertheless retains the advantages of the present invention.

50 In the present case the invention is illustrated as applied to a so-called six-spot system, but any number of spots may be used and, in fact, other 55

arrangements than those indicated in the drawings may be employed, as, for instance, a circular group or a group forming other configurations in a plane or in a three-dimensional space. In 5 the embodiment herein described six hydrophones are installed on the starboard side of the vessel and six hydrophones on the port side. Selector switches are then provided so that the six starboard hydrophones may be employed to listen to sounds approaching from the starboard side of 10 the vessel or the six port hydrophones may be employed to listen to sounds approaching from the port side of the vessel, or three of the starboard hydrophones and three of the port hydrophones may be employed as a cross base to listen to sounds coming from ahead.

In Fig. 1 the coils of the port receivers are represented by 1'p, 2'p . . . 6'p while the coils of the six starboard receivers are indicated as 20 1's, 2's . . . 6's. The hydrophones used in connection with this compensator are matched directly with the lines on which the sound energy is impressed. The direct current flux excitation is supplied in series groups of three; the switches 25 13' and 9 applying the potential of the battery 13 across the common 14 and each of the groups of windings 12. A selector switch 15 is provided which has three positions: a bow position as indicated in the position shown in Fig. 1, a port 30 position when rotated to the left and a starboard position when rotated to the right. For the bow position it will be noted that there is a choice of the use of the forward groups or the aft groups of three receivers. This choice may be effected 35 by the jumper connectors 7 and 8 which connect the switch arms 9 and 10 to the connecting points F' on the left or A on the right.

The jumpers 7 and 8 are preferably fixed when 40 the installation is made for the best choice on the vessel and thereafter are not changed unless it is especially desired to do so. In the position of the jumpers indicated in Fig. 1, it will be noted that the forward group F connecting with 1'p, 2'p, 3'p and 1's, 2's and 3's is used. In the position of the jumpers on the right contact points 45 A the receivers 4'p, 5'p and 6'p and 4's, 5's and 6's would be connected to the compensator. The switch 9 in its downward position is connected with the two switch points whose combination is 50 designated 9B. In this relation the jumpers 8 sloping to the left energize the coils in the receivers 1'p, 2'p, 3'p and 1's, 2's and 3's. With the jumpers 8 in the other position the rear or aft group of receivers would be energized.

55 In the position for bow compensation, as indicated by the position of the switch 15, the end switch arms 11 and 11' connect the receivers with fixed compensation directly to the binaural line indicated at the top of the figure. In the 60 position shown in Fig. 1 the receiver 1'p is connected to the C-line at its left end. The receiver 2'p is connected through the switch point 2B at the end of the fixed or F-line while the receiver 3'p is connected at the right end of the C-line. 65 The energies from the receivers thus compensated in a fixed fashion are impressed by means of the connecting lead 16 to the common of one-half of the B-line as indicated by the numeral 17 applied to the right half of the ring 18.

70 Similarly the starboard half group is connected to the left connector 19 of the ring 18 by means of the connecting lead 21. In this case the starboard receiver 1's connected through the 4B position of the switch 10 connects to the left end 75 of the C-line while the receiver 3's connects

through the switch point 6B to the right of the C-line, and the receiver 2's connects through the switch point 5B to the F-line. The energy from the three receivers is conducted over the line 22 to the B-line through the lead 21 and also to one 5 terminal 23 of the binaural headphone 24. The other phone lead 25 connects to the opposite end of the B-line and similarly also one terminal of the phone 26 is connected to the other extreme end of the B-line. 10

The description above illustrates the switching arrangement for the so-called bow position.

In the port and starboard positions the switch arm 15 is moved to the left and right, respectively, that is to the left for the port position and 15 to the right for the starboard position. In the port position the receivers 1'p, 2'p and 3'p are connected to the left end of the C-line, the end of the F-line and the right end of the C-line, respectively. The switch 11 in the position at 20 the left connects the F-line to the switch contacts 62, 29 and 63 by means of the lead 27. Similarly the switch 11' in the position 11'p connects the F-line to the switch contacts 64, 30 and 65 by means of the lead 28. The switch 25 contacts 62, 29 and 63 and 64, 30 and 65, respectively, unite the impulses passing through each F-line and its corresponding C-line at the correct points to produce the desired compensation to compensate for the difference in time 30 of arrival of the wave energy at the receivers of each group.

As will be noted, the switch contacts 62, 20 and 63 and 64, 30 and 65 are adapted to move 35 over the contact studs 31 to 36', inclusive, and 37 to 42', inclusive, respectively, each stud connecting to a different point on the left and right C-lines, respectively. The contact switches 62, 20 and 63, and 64, 30, and 65 move simultaneously on the same mechanism as the ring 18 and the 40 switch brushes 43, 51 and 44: the position of the contact switches 62, 20 and 63, and 64, 30 and 65 adjusting the compensation of the C-lines and the position of the ring 18 and the contact brushes 43, 51 and 44 adjusting the compensation 45 of the B-line.

As indicated in Fig. 1 the energy from the left F- and C-lines is fed into the B-line by the two conductors comprising the lead 16 together with a portion 17 of the ring 18 and the brushes 44 50 and 57 while the energy from the right F- and C-lines is fed into the B-line by means of the conductors 22 and 21 together with the portion 19 of the ring 18 and the brushes 43 and 57. The ring 18 and the brushes 43, 57 and 44 move simultaneously breaking the B-line each half section 55 in its motion. This is accomplished as follows:

The B-line is composed of series inductances 46, 46, etc., which with the condensers 50, 50, etc., 60 form the sections of the line. The condensers 50 are connected between the series inductances and the common. The line sections may be considered as either T sections or π sections, and are, in fact, first one and then the other, depending upon the switch positions. It should be noted, however, that whether the sections are considered to be π or T sections, there is required only one two-terminal inductance coil per section. The condensers 50, 50, etc., are connected by means of the brushes 51, 51, etc., to the ring 18, while the 65 inductances 46, 46, etc., are connected together in series and are also connected at their junctions to the studs 52, 52, etc.

Between the halves 17 and 19 of the ring 18 70 there is an insulating element 53 which carries 75

two conducting segments 54, 55 spaced somewhat less than the width of the brushes 51 from the segments 19 and 17, respectively, of the ring 18. These segments 54 and 55 are connected to the segments 19 and 17 through condensers 56 and 57 of the same capacity as the condensers 50.

Between the brushes 43 and 57 there is connected an inductance 71 of the same value as the effective series inductance per section of line. Likewise between the brushes 57 and 44 there is connected an inductance 72 of the same value as the inductance 71. By making the values of the inductances 71 and 72 of the same value as the effective series inductance of the line, in this case substantially that of coils 46, the effective terminating inductance for each half of the line will be equal to half of the inductance of coil 46 since both 71 and 72 are connected in parallel with one of the coils 46.

In the C-lines the inductances are all connected in series and each of their connecting points are also connected to a contact stud. The condensers making up the C-lines are shunted between the connecting points of the inductances and a common. The adjustment of the C-lines is not made by opening the common as in the case of the B-line, but by connecting to the junction points of the series inductances.

The brushes 62, 20, 63, and 64, 30, 65 divide each of the two C-lines into two parts, respectively. Inductances 58, 59, 60 and 61 are connected between the several brushes, as shown, in order that the parts of the C-lines may be given proper terminations. The operation of the C-line adjustment is indicated in Fig. 2 by the development of the switch controlling the left C-line.

In the position *a* the brushes 62, 63 are making connection with the contact studs 35 and 34, respectively. The inductances 58 and 59 each have an inductance of a value one-half that of the effective series inductance per section of line. The energy is taken off the line through the brush 20 which in position *a* connects to the line only through the inductances 58 and 59. If we suppose the energies entering at each end of the line arrive in phase at coil 73, then coil 73 will be at a current node. Therefore, the coil 73 has no effect at all and one half of the line is terminated in the inductance 58 while the other half of the line is terminated in the inductance 59. Thus, since each coil 58 and 59 has an inductance of a value one half that of the coil 73, each half of the line will be terminated perfectly in a mid-series manner by the coils 58 and 59.

In the prior art when a single brush was used, it was ordinarily made of sufficient width to connect at times simultaneously to two adjacent studs. When the direction of sound was such as to produce a current node in one coil, the proper setting of the switch would shortcircuit this coil and the line would not be properly terminated. It will be apparent, however, that with the arrangement of the present invention, the C-line may be given perfect mid-series terminations.

Position *b* shows a transient position of the switch in which the line terminations are being changed from those in position *a* to those in position *c*. In position *c* the brush 20 contacts with the stud 34 while the brushes 62 and 63 are not connected to the line. The inductances 58 and 59 are therefore inoperative when the switch is in this position and both the left and the right parts of the line have a mid-shunt termination. The position *d* again shows a transient position of the brushes while position *e* is similar

to position *a* but one section advanced to the right.

In practice it is often convenient to use brushes and contact studs which have a considerable width. If this is the case it is necessary to have a certain relationship between the width and the spacing of the brushes with respect to the width and spacing of the contact studs. The proper width and spacing of the brushes with respect to the width and spacing of the contact studs will be apparent from a consideration of Fig. 2. Each of the three brushes 62, 20 and 63 has the same width *b* while the distance between them is the same as the width *S* of each of the studs 31 to 36'. Then if we let *P* be the distance between centers of adjacent studs and *B* be the total distance spanned by the three brushes, the following relations will hold:

$$b=0.5 P-S$$

and $B=1.5 P-S$ 20

It will be noted that the dimensions of the development of the switch as shown in Fig. 2 agree with the above formulas. The specific example shown, however, is a particularly convenient one inasmuch as the width of the brushes *b* is made equal to the width *S* of the studs. It will be observed, however, that any desired choice can be made of either *b* or *S* and that such choice will determine the value of the other dimensions. 30

Fig. 3 shows schematically an alternative manner of connecting the hydrophones and telephones to the retardation lines from that shown in Fig. 1. In the embodiment described in Fig. 1 the C-lines are shown as feeding to the center of the B-line through the brushes 43, 51 and 44 while the telephones are connected to the ends of the B-line. It will be obvious, however, that the opposite system may be employed if desired. This is shown in Fig. 3. In this figure the C-lines feed 40 to the ends of the B-line and the telephones are connected to the center of the B-line through the brushes 43, 51 and 44. An important difference between the two is that with the latter arrangement the two C-lines must have separate commons. On the other hand, if separate commons are used, the telephone transformers 68 and 69, Fig. 1, may be omitted as shown in Fig. 3. 45

In any case, it will be apparent, of course, that microphones may be employed instead of 50 magnetophones. However, if microphones are used, it will generally be preferable to connect them to the compensator through transformers rather than directly.

The allowable size of section of the B-line is 55 determined by the accuracy of observation of the binaural method or by the minimum perceptible difference in the maximum method of observation, and the spacing of the hydrophones. Usually the size of a section is approximately 1.8 60 water inches. In the present case I may use a section having about 3 water inches retardation and may also use the same size section for the C-line. In the present invention the B-, C- and F-lines have the same cutoff frequency and have 65 their impedances rather well matched and absolutely matched under the same conditions of termination of the B- and C-lines.

When the compensator is used for the maximum method the switch 70 must be closed. This 70 switch connects the secondaries of the transformer 68 and 69 in parallel for the maximum method. The primaries of the transformers 68 and 69 are matched to the line. The transformers may be omitted if it is desired only to 75

use the binaural method or if, as above described, the C-lines have separate commons.

While the invention has been described above as applied to a compensator for use in systems for finding the direction of a source of sound waves, it will be apparent that it has other applications. Furthermore, it is useful not only in connection with retardation lines having series inductances and shunt capacitances, but also with other types of artificial lines or series of electrical structures. It should be noted that the line may be composed of impedances in any form including mutual inductance if desired and that the bridging elements may be impedances of any suitable form. The bridging elements and a switch of any of the types described may, for example, be used with a lattice line or with a line having series capacitances and shunt inductances.

Accordingly, it will be appreciated that the present invention can be embodied in other forms and therefore I do not desire to limit myself to the embodiment herein described, but I claim:

1. An electric compensator including an artificial line comprising inductive series elements each having an inductance of L and capacitive shunt elements forming sections of the line, switching means for adjusting the length of the line and adapted to place two series connected inductance elements each having an inductance of

$$\frac{L}{2}$$

in parallel with one of said inductive series elements and means for supplying electric energy to the connection between said series connected inductance elements.

2. The combination of an electrical network having a series of recurrent structures each con-

taining a series impedance element having only two terminals with means for effectively connecting to the electrical center of one of said impedance elements including a pair of series connected impedances each having one half the impedance of said series impedance elements and being adapted together to be connected in parallel with one of said series impedance elements and means for transferring electric energy to the common terminal of said series connected impedances.

3. In an electric compensator including series and shunt impedance elements forming sections of an artificial line, switching means for varying the length of the line including a plurality of 15 contact studs connected one to each junction of two adjacent series elements and three brushes movable simultaneously with respect to said studs, the widths and spacing of the brushes being so adjusted with respect to the width of the 20 studs that the width of each brush is $0.5 P - S$ and the total span of the three brushes is $1.5 P - S$ where P is the distance between centers of adjacent studs and S is the width of each stud.

4. The combination of an electric retardation 25 line having a series of recurrent sections each containing a series inductive impedance element, means for feeding electrical energy to the line between an interior section and each end of the line, said section being in such a position that 30 there is a current node in its series impedance element, said means including a switching device having a center tapped impedance element adapted to be connected in parallel with one of 35 said line impedance elements and said center tapped impedance element having an inductance equal to the inductance of said line impedance element.

LAURENCE BATCHELDER.
